(57) **CLAIM**

The ornamental design for a memory storage device with snowboard housing, as shown and described.

DESCRIPTION

FIG. 1 is an exploded perspective view of the memory storage device with snowboard housing showing our new design;

FIG. 2 is an exploded side view thereof, the opposite side being a mirror image;

FIG. 3 is an exploded bottom view thereof;

FIG. 4 is a front view thereof;

FIG. 5 is rear view thereof; and,

FIG. 6 is a top view thereof.

The broken lines showing the pattern of the connector in FIGS. 1 and 3 are for illustrating environmental structure and form no part of the claimed design.
